(57) CLAIM

The ornamental design for a bag as shown and described.

DESCRIPTION

FIG. 1 is a top, front, right perspective view of a bag showing our new design;

FIG. 2 is a bottom, rear, left perspective view thereof;

FIG. 3 is a top view thereof;

FIG. 4 is a bottom view thereof;

FIG. 5 is a right side view thereof;

FIG. 6 is a left side view thereof;

FIG. 7 is a front side view thereof; and,

FIG. 8 is a rear view thereof.

The broken lines illustrate portions of the bag which form no part of the claimed design.

1 Claim, 8 Drawing Sheets
